(57) **CLAIM**

The ornamental design for a display screen or portion thereof with animated graphical user interface, as shown and described.

DESCRIPTION

FIG. 1 shows a display screen or portion thereof with graphical user interface showing our new design; FIG. 2 shows a second image thereof; and, FIG. 3 shows a third image thereof.

The peripheral dashed broken lines illustrate a display screen or portion thereof, and form no part of the claimed design.

The text, symbols, and icons illustrated in broken lines form no part of the claimed design.

The appearance of the animated graphical user interface transitions sequentially between the images shown in FIGS. 1-3. The process or period in which one image transitions to another forms no part of the claimed design.
